US0D1009558S

(12) **United States Design Patent** (10) Patent No.: **US D1,009,558 S**
(45) Date of Patent: ** Jan. 2, 2024

(54) **FOLDABLE TEA STRAINER**

(71) Applicant: **Ning Guo**, Huizhou (CN)

(72) Inventor: **Ning Guo**, Huizhou (CN)

(73) Assignee: **Ning Guo**, Huizhou (CN)

(**) Term: **15 Years**

(21) Appl. No.: **29/811,238**

(22) Filed: **Oct. 13, 2021**

(30) **Foreign Application Priority Data**

Sep. 27, 2021 (CN) 202130641899.6

(51) **LOC (14) Cl.** **07-06**

(57) **CLAIM**

The ornamental design for a foldable tea strainer, as shown and described.

DESCRIPTION

FIG. 1 is a perspective view of a foldable tea strainer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the foldable tea strainer where the foldable tea strainer is in a first configuration of use; and,

FIG. 10 is a perspective view of the foldable tea strainer where the foldable tea strainer is in a second configuration of use.

The broken lines in the drawings depict portions of the foldable tea strainer that form no part of the claimed design.

1 Claim, 10 Drawing Sheets
